UNITED STATES PATENT OFFICE.

WILLIAM S. THOMSON, OF PLANTSVILLE, CONNECTICUT, ASSIGNEE TO THE H. D. SMITH & COMPANY, OF PLANTSVILLE, CONNECTICUT, A CORPORATION.

PLIERS AND SIMILAR TOOL.

1,159,621.

Specification of Letters Patent. Patented Nov. 9, 1915.

Application filed February 4, 1915. Serial No. 6,068.

To all whom it may concern:

Be it known that I, WILLIAM S. THOMSON, a citizen of the United States, residing at Plantsville, in the county of Hartford 5 and State of Connecticut, have invented certain new and useful Improvements in Pliers and Similar Tools, of which the following is a specification.

My invention relates to improvements in 10 pliers and similar tools, having particular reference to the means for interconnecting the members thereof, and the object of my improvement is simplicity and economy in construction and convenience and efficiency 15 in use.

In the accompanying drawing:—Figure 1 is a front elevation of a pair of pliers embodying my invention. Fig. 2 is a side elevation of the same. Fig. 3 is a front elevation 20 of a modification and with the parts in the open position. Fig. 4 is a sectional view on an enlarged scale on the line $\alpha\alpha$ of Fig. 1. Fig. 5 is a view corresponding to Fig. 1 and on the same scale of a modification showing 25 a pivot pin.

The pliers shown in Fig. 1 embodying my invention, comprise a pair of similar members 10 having pinching jaws 11 at one end and handles 12 at the other end, the said 30 members being pivotally connected at the portions 13 intermediate the said ends in a special manner to be described. The said intermediate portions 13 are circular in formation, having opposed faces 16 in abut- 35 ment, and they are provided with radial recesses that coöperate to serve as cutting jaws. A plurality of such recesses is shown, comprising lateral recesses 14 at each side and axial recesses 25 that are located at the bases 40 of the pinching jaws 11.

The special means of pivotally connecting the members 10 involve the following construction. It will be noted that the members 10 cross at the point of pivotal connection, as is usual with pliers, the pinching jaw 11 of one particular member being on the opposite side of the axis as the handle 12 of the said members. The shank portion of each member between the handle 12 50 and the overlapping intermediate portion 13 is thickened or swelled as shown at 15 so as to extend above the bearing face 16, and preferably so that the outer face of the thickened portion 15 is flush with the adj-

cent outer face of the intermediate overlapping portion 13, as will be noted in Fig. 4. The swelled portion 15 referred to of each member will be on one side of the pivotal axis. On the side diametrically opposed to the swelled shank portion 15 the pinching 60 jaw is similarly swelled or thickened, as will be also noted from Fig. 4, and as shown at 17. That is to say, the thickness of the pinching jaws 11 and the shank portions 15 correspond essentially to the combined thickness 65 of the overlapping portions 13. The features so far described are usual in pliers. I utilize the thickened shank portion 15 and the thickened pinching jaw portion 17 as means for holding the members 10 pivotally 70 connected, and this feature I believe to be new.

Referring to the sectional view in Fig. 4 it will be noted that the overlapping portions 13 comprise a cylindrical wall portion 75 18 adjacent the bearing faces 16 and exteriorly of the same there is a conical portion 19, comprising essentially a tapering or removal of the corner of the outer end of the cylindrical portion 18. Of course, the relative proportions of the cylindrical portion 80 18 and the tapered portion 19 may be varied according to any degree desired, so long as a reduced portion 19 is provided of appreciable extent. That is to say, for the tapered form shown for the reduced portion 85 19 a different form may be provided than that shown.

In order to complete the joint, operatively uniting the members 10, the swelled portions 90 15 and 17 are made to fit the opposed walls of the overlapping portions 13. As shown this consists of providing a cylindrical portion that fits against the cylindrical portion 18, and which consists of the body material 95 and an overhanging portion 20 that fits over the tapered or reduced portion 19 of whatever particular form the same may be.

As the opposed or engaged portions are of circular formation being concentric with the 100 pivotal axis, and each consists of an appreciable arc, the joint provided serves to positively unite the members 10, and so as to permit of relative pivotal movement, the joint being what may be styled an incased 105 joint.

It will be noted that the pivotal connection is provided without the use of a piv-

otal pin, although such a pin 21 may be provided in some cases, as in the modified form 10^a shown in Fig. 5.

An advantage that is possible with the in-
5 cased joint shown and described and parti-
cularly applicable to the form omitting
the pivotal pin is found in the modification
shown in Fig. 3 and applied to the radial
cutting jaws, such as the jaws 25^a provided
10 in members 10^b shown in the said figure.
It will be noted that these jaws may be made
of any depth desired, so long as the mem-
bers 10^b are not cut in two, the practical
limit being to have the depth of the jaw
15 forming recesses terminate at the pivotal
axis, where the cutting movement will be
zero.

Of course, as the depth of the jaw re-
cesses 25^a is increased the cutting movement
20 will be reduced, the limit being zero, as men-
tioned, and as the cutting movement is re-
duced the cutting leverage is increased, so
that with a deep recess 25^a a corresponding
powerful cutting effect will be produced.

25 It will be noted that means are provided
for pivotally connecting the members 10 that
are integral with the said members, so that
the complete tool may consist of simply two
parts, the flange-like overhanging portion 20
30 serving to hold the members together. Any
form of pinching jaws may be provided, or
these may be omitted altogether. Also, the
pinching jaws may be omitted or these may
35 be replaced by some form of cutting jaws.

I claim as my invention:—

1. Pliers comprising a pair of mating
members, the said members being similar
and having overlapping portions of circu-
lar formation, said overlapping portions
having their exterior portions reduced at the
edges, and the said members having each
45 diametrically disposed and inwardly directed
flanges engaged with the said exterior re-
duced portion of the other of the said mem-
bers.

2. Pliers comprising a pair of mating
members, the said members being similar
and having overlapping portions of circular
formation, said overlapping portions hav-
ing their exterior portions reduced at the 50
edges, and the said members having each
diametrically disposed and inwardly directed
flanges engaged with the said exterior
reduced portion of the other of the said
members, and the said overlapping portions 55
being provided with radial slots that co-
operate to serve as cutting jaws.

3. Pliers comprising a pair of similar, co-
operating members having circular overlap-
ping portions, each of the said members hav-
ing flange portions on each side of the axis,
and the said flange portions extending in-
wardly so as to overhang the opposed edge
of the mating member suitably to prevent
separation of the said members. 65

4. A pair of members having overlap-
ping portions provided with radial cutting
jaws, the said cutting jaws being formed by
radial recesses that extend to the pivotal
axis of the said members, the said members 70
being similar, and each being provided with
diametrically disposed flanges that extend in-
wardly so as to overhang the opposed edge
portion of the mating member.

5. Pliers comprising a pair of mating 75
members, the said members being non-sepa-
rably connected together by means of an in-
cased joint, and the said joint comprising cir-
cular overlapping portions, shoulders diamet-
rally disposed on each member and en-
gaged with the opposed edge portion of the
other member, and flanges extending in-
wardly from the outer portions of the said
shoulders suitably to overhang the said edge
portions of the other member. 80
